UNITED STATES PATENT OFFICE.

CALEB B. WASHBURN, OF MINNEAPOLIS, MINNESOTA.

MANUFACTURE OF BARRELS.

SPECIFICATION forming part of Letters Patent No. 296,091, dated April 1, 1884.

Application filed November 5, 1883. (No model.)

To all whom it may concern:

Be it known that I, CALEB B. WASHBURN, a citizen of the United States, residing at Minneapolis, in the county of Hennepin and State of Minnesota, have invented a new and useful Improvement in the Manufacture of Barrels, of which the following is a specification.

My invention relates to an improvement in the manufacture of barrels; and its object is to afford an effective means for overlapping and closing interiorly the seams or cracks between the staves, thus making a barrel that will be practically tight when from expansion or other cause the staves do not fit closely. I attain this object by inserting strips of wood, suitably beveled, into dovetail grooves cut into the edges of the inner face of the staves, as illustrated in the accompanying drawings, in which—

Figure 1 is an elevation of the barrel with a portion of one side removed, showing the inner surface of the opposite side. Fig. 2 represents two of the staves before being bent, showing the grooves *c* and the straight strip *a*. Fig. 3 is a top view of the lower half of the barrel on the line *d d* of Fig. 1; and Fig. 4 is a cross-section of two staves and the strip, showing their relative positions in the finished barrel.

The staves *b* have grooves *c* along their inner edges, of such shape that when the staves are placed with their outer edges together the cavity formed by the grooves along their inner edges will have a greater width at its bottom than at its surface, and the strips *a* have their edges so beveled that they will fit into and fill such cavity.

In constructing a barrel according to my invention, strips may be used of any convenient width and thickness, so beveled or cut away as to fit into grooves cut into the staves for their reception; but I prefer using such as are about one and one-fourth inch wide and one-fourth inch thick, with the edges along one face beveled, each one-eighth of an inch. The staves then should be so grooved along their inner edges that when placed side by side, with their edges meeting, the beveled strips will fill the dovetail groove thus formed and their faces be flush with the inner surface of the barrel. Thus in using strips *a* of the form and size suggested, the grooves *c* in each stave should be one-fourth inch deep by five-eighths ($\frac{5}{8}$) inch wide at the bottom and one-half ($\frac{1}{2}$) inch wide

at the surface, making the cavity, when the staves are joined, a dovetail groove of the exact size of the strips, so that when the strips are inserted their faces will be flush with those of the staves. These strips or splines may be inserted during or after the setting up of the barrel. In hand-made barrels, I prefer fitting in the strips as the staves are being set up—that is, by setting up a stave, then inserting a strip in the groove, then placing the next stave, then its strip, and so on until all are in place. In machine-made barrels having the proper grooves, the strips may be inserted from the top after the barrel has been set up, and can be pressed down into the grooves.

I am aware that prior to my invention splines similar to those I use were used in grooves cut along the outside edges of the staves, in connection with pins and an adhesive substance as aids in keeping the splines in place; but I regard my invention as an improvement upon such method, for the following reasons: In using outside splines some such aids as pins and glue would be required to keep the splines in place, for the staves hold them by only a narrow projecting edge, which would cease to engage them so soon as a slight separation of the staves took place from expansion or other cause, when they would be held only by the hoops above and below, and would bow out in the middle, and with such aids as pins and glue in barrels made of thin staves—such as flour-barrels and the like—a slight expansive force would be sufficient to break the glue and release the pins, when the splines would be free to bow outward at their middle. In my barrel, on the other hand, the splines or strips need no pins or glue or other aids to hold them in place, for any expansion of the wood of the barrel or of the substance contained within would only tend to press the splines more firmly in their grooves. In the former barrel the staves must be secured very close together, or the spline will be of no advantage. In mine the staves may separate to almost the width of the strip and the seam still be effectually closed. Further, when the hoops are loosened to allow the removal of the head and of its being replaced when desired, (as with flour-barrels and others similarly used,) outside splines would spring out of place near the top, the glue would be broken, and the pins displaced, and these would be required

to be renewed when the head is replaced. In using my inside strips these difficulties are avoided, for such loosening of the hoops does not cause the strips to spring out of their grooves, and the head can be replaced and the hoops tightened just as with the common barrel. I save the expense and labor occasioned by using pins and an adhesive substance, and also am able to insert my splines with less difficulty than the outside splines, for the reason that the latter have only the narrow projecting edge of the groove on one side to hold them until the next stave is placed, and they tend constantly to spring away, while in setting up my barrel they press against the back of the groove, and there is no trouble in keeping them in place. In barrels made of light material great care and nicety of workmanship would be necessary to insure even a fairly smooth exterior in making the barrel with the outside splines. My inside splines do not in any way interfere with the smoothness of the exterior barrel. Again, in the former barrel the material removed for the grooves on the outside and for the head inside weakens the chine at that point, which is not the case in my use of the strips. My use of such splines

inside instead of outside is a saving in the cost of the barrel, the barrel produced is of smoother exterior finish, the seams are more effectually overlapped when expanded, and in flour-barrels and other barrels intended to be similarly used less labor is required in removing and replacing the heads. While the former barrel was designed for kerosene-oils and burning fluids of different kinds, mine is found to be especially useful for flour and like substances, which, while requiring a tight barrel, are usually packed in such as are made of light material and are cheap.

Having fully described my invention, what I claim, and desire to secure by Letters Patent, is—

The combination, in a barrel, of staves having their inner edges cut away to form dovetail grooves, with strips of wood beveled suitably to fit into and fill such cavities flush with the inner surface of the staves, while permitting their outer edges to meet.

CALEB B. WASHBURN.
